(57) **CLAIM**

We claim the ornamental design for an ant bait station, as shown and described.

DESCRIPTION

FIG. 1 is a perspective view of an ant bait station, showing our new design;

FIG. 2 is an exploded perspective view thereof;

FIG. 3 is an exploded front elevational view of FIG. 2, the rear elevational view being a mirror image thereof;

FIG. 4 is an exploded left-side elevational view of FIG. 2, the right-side elevational view being a mirror image thereof;

FIG. 5 is an exploded top plan view of FIG. 2; and,

FIG. 6 is an exploded bottom plan view of FIG. 2.

The broken lines showing text in the figures depict environmental matter and form no part of the claimed design.
